Frank Warren.

UNITED STATES PATENT OFFICE.

HANS G. HANSEN, OF RICHMOND BEACH, WASHINGTON.

MILK-CAN.

1,377,341.

Specification of Letters Patent.

Patented May 10, 1921.

Application filed May 3, 1920. Serial No. 378,691.

To all whom it may concern:

Be it known that I, HANS G. HANSEN, a citizen of the United States, residing at Richmond Beach, in the county of King and State of Washington, have invented a certain new and useful Improvement in Milk-Cans, of which the following is a specification.

My invention relates to metal cans and relates more particularly to the type of cans used for the transportation and storing of milk and the object of my invention is to provide a milk can wherein the seams are formed in such a manner that milk or dirt may not lodge or collect therein thus avoiding the formation of any bacteria therein.

A further object is to provide a milk can so constructed that when disfigured will not break at the seams. A still further object is to provide a milk can that is adaptable to withstand the hard usage given the same, that is uniformly strong throughout, that embodies simplicity, durability and economy in weight and construction and that may be easily cleaned after use.

With the above and other objects in view which will appear as the description proceeds, the invention resides in the novel construction, combination, adaptation and arrangement of parts hereinafter described and claimed.

I accomplish these objects by devices illustrated in the accompanying drawings, wherein—

Figure 1 is a view of a milk can embodying my invention, the left half of which is in side elevation and the right half in medial vertical section; and

Fig. 2 is a top plan view of the same. Referring to the drawings throughout which like reference numerals indicate like parts, the numeral 5 designates the bottom plate or base, 6 the body or central section, 7 the body hoop or ring, 8 the breast or upper section, 9 the neck hoop or ring, 10 the neck or bowl, and 11 the hand holds.

The bottom plate 5 is concavo-convex in form and is provided with an upwardly projecting peripheral flange 12 having an annular groove 13 formed in its upper face.

The lower end of the central section 6 is adapted to seat within the annular groove 13 being fixedly secured therein by the solder 14.

The hoop or ring 7 is provided with an annular groove 15 on its lower face and with

a similar groove 16 on its upper face. The upper end of the body section 6 is adapted to seat within the annular groove 15 formed on the lower face of the ring 7 being fixedly secured therein by the solder 17.

The lower end of the breast or upper section 8 is adapted to seat within the annular groove 16 being fixedly secured therein by the solder 18.

The neck hoop or ring 9 is provided with an annular groove 19 on its lower face and with a similar groove 20 on its upper face. The upper end of the breast or upper section 8 is adapted to seat within the annular groove 19 formed on the lower face of the ring 9 being fixedly secured therein by the solder 21.

Disposed within the annular groove 20 of the neck ring 9 is the lower end of the neck 10 or bowl 10 which end is fixedly secured therein by the solder 22.

The upper portion of the neck 10 is adapted to flare outwardly in a well known manner and is provided on its upper outer rolled edge with a reinforcing wire ring 23.

The hand holds 11 are fixedly secured to the upper section 8 by rivets 24.

I have also provided a dished cover 25 of well known form that is adapted to seat 85 within the neck 10, which cover is provided with a hand hold 26.

It will be clear from the foregoing description taken in connection with the accompanying drawings that the construction 90 described and disclosed provides a perfectly smooth interior surface within the can thus eliminating crevices wherein dirt milk or any foreign substance may lodge which ordinarily is the cause of the formation of 95 bacteria.

This construction also permits of a thorough sterilization of the can after its contents have been disposed of. It will also be obvious that should the can be disfigured 100 adjacent the seams or joints of the elements comprising the same, the said seams or joints will not spread or spring thereby causing a leakage as frequently occurs in milk cans having riveted joints.

From the foregoing description taken in connection with the accompanying drawings, the advantages of the construction and of the method of operation will be readily apparent to those skilled in the art to which 110 the invention relates, and while I have described the principle of operation of the

invention, together with the device which I now consider to be the best embodiment thereof, I desire to have it understood that the device shown is merely illustrative and 5 that such changes may be made when desired as are within the scope of the invention.

What I claim is:

In a milk can comprising a concavo-convex bottom plate, an upwardly projecting peripheral flange formed thereon having an annular groove in the upper face thereof, a body section having its lower ends adapted to be fixedly secured within said 10 annular groove, a hoop having annular grooves formed in its upper and lower faces, said lower annular groove being adapted to receive the upper end of the said body section which is adapted to be fixedly secured 15 therein, a curved upper section having its 20

lower end adapted to be secured within said upper annular groove of said hoop, a neck hoop having annular grooves formed in its upper and lower faces, the said lower annular groove in said neck hoop being adapted 25 to receive the upper end of said curved upper section which is adapted to be fixedly secured therein, an upwardly flaring neck section having its lower end adapted to be fixedly secured within said upper groove 30 formed in said neck hoop and having its upper flared end rolled to form a peripheral channel, a reinforcing ring disposed in said channel, a closure for said can, a hand hold for said closure, and a plurality of 35 hand holds fixedly secured to said upper curved section.

In witness whereof, I hereunto subscribe my name this 26th day of April A. D. 1920.

HANS G. HANSEN.
